UNITED STATES PATENT OFFICE.

CHARLES E. FOSTER, OF WASHINGTON, DISTRICT OF COLUMBIA, ASSIGNOR
TO THE TROJAN CAR COUPLER COMPANY, OF TROY, NEW YORK.

VESTIBULE-CAR.

SPECIFICATION forming part of Letters Patent No. 596,866, dated January 4, 1898.

Application filed May 5, 1897. Serial No. 635,183. (No model.)

To all whom it may concern:

Be it known that I, CHARLES E. FOSTER, a citizen of the United States, residing at Washington, District of Columbia, have invented 5 certain new and useful Improvements in Vestibule-Cars, of which the following is a specification.

My invention relates to that class of cars known as "vestibule-cars," and has for its 10 object to maintain the face-plates of the said cars in contact with each other; and to this end it consists in the combination, with the cars and face-plates and buffer-beams to which the face-plates are connected, of a rod or rods, 15 and cables connecting the rods and the buffer-beams in such manner that any inward movement imparted to the upper part of the face-plate will be transmitted through a positive cable connection to the lower part thereof or any outward movement of the lower end 20 of the face-plate will be transmitted to the upper end thereof, as fully set forth herein-after and as illustrated in the accompanying drawings, in which—

25 Figure 1 is a transverse sectional elevation of the end of a passenger-car provided with my improvement. Fig. 2 is a plan view showing one of the face-plates and its attachments disconnected from the car. Fig. 3 is a plan 30 view showing a modification. Fig. 4 is a sectional view showing another modification.

The body and frame of the car are of usual construction, with a platform A and overhanging hood J, with the frames for the side doors 35 and the frame I for the central passage, as usual.

Beyond the end beam D of the platform is the buffer-beam E, of metal, supported to move in and out under the action of springs, 40 as usual. Thus, as shown, there is a central bar n' passing through the cross-beams of the platform and having a collar m bearing against a spring p, which in turn bears against one of the other cross-beams, so that 45 the buffer-beam E can move inward only against the stress of the spring p. With the buffer-beam E is connected the usual face-plate B, and between the latter and the frame I is arranged the usual bellows siding.

50 Below the hood J slides one or more rods b, one being shown in Figs. 1 and 2 and two being shown in Fig. 4. When a single rod is

used, it passes through the center of the frame I above the opening therein, and when two are used, as shown in Fig. 4, they pass through the frame at opposite sides of the same, and the outer end of the rod or rods in any case will bear against or be connected to the inner face of the face-plate B. As shown, the end of each rod b has a pin e, which passes through 60 an opening or eye in an ear n at the inner side of the face-plate B, so that the latter can move up and down to a limited extent without straining the rod b.

With the rear end of each rod b is connected 65 the rear end of a flexible non-extensible cable d, which passes over a guide-pulley s and down and under a guide-pulley i, the lower end being connected with the face-plate or buffer-beam E either directly or indirectly. 70 As a result of this construction the lower part of the face-plate B or buffer E is flexibly but positively connected with the rear end of the rod or rods b. Therefore if the beam E is drawn outward the draft upon the cable d 75 will draw outward the rod or rods b, while if the plate B or the buffer-beam E is pushed inward the cable d, while it will be relaxed at the lower part, will be taken up at the upper part by the inward movement of the rod 80 or rods b. It will be seen that this action takes place regardless of the presence of the spring p, and if the buffer-beams E were connected together in any manner the result 85 would be the same whether the spring p was present or not. The spring, however, is of course a desirable incident to the use of the part E as a buffer-beam and acts in the usual manner whether the face-plate B is present or not, so far as the buffer-beam E is concerned. 90

The cable d may extend from the beam E to the end of the rod b, or it may be preferably connected with an eyebolt c, threaded and passing through a collar a' on the rod b, with 95 nuts f, by means of which the cable may be tightened when it is put in place and in case of any slack from use. If the cable d did not stretch under use, the original adjustment of the parts would be sufficient, but as 100 it is not only liable to stretch but to elongate from atmospheric changes it is preferable to provide some means whereby slack can be taken up or the tauting of the cable can be

prevented from straining it to an excessive extent. I therefore prefer to provide some means for yielding to the tightening action and for taking up slack. Thus the pulley i 5 may be carried by a lever g , against which bears a spring t below the platform, whereby the depressing of the lever is the means of maintaining the cable taut. Instead of this a spring may be put in the line of the cable— 10 say, for instance, in the horizontal portion below the platform—or instead of this there may be two pulleys $i' i''$, arranged as shown in Fig. 4, and another pulley i^2 , under the action of a spring t' , may, by bending up the 15 cable between the pulleys $i' i''$, take up any slack and yield if the cable should become taut. It will be seen that however the spring may be arranged it simply acts as a means of taking up slack or preventing the cable from 20 becoming too taut, but that practically the connection between the buffer-bar E and the rear end of the rod or rods b is an unyielding positive connection for transmitting the movement of the lower part of the face-plate to the 25 upper or from the upper to the lower, as any outward movement of the bar E will draw on the cable and carry out the rod b , and any inward movement of the latter drawing on the cable will draw in the bar. 30 While I have shown the rod b as connected with the inner side of the face-plate, this is not absolutely necessary, as the ends of the rods might simply bear against the inner face of the plate, and it will be evident that the 35 said rod or rods b may be supported and guided in any suitable manner.

When there is but a single rod b , the collars a' are practically the end of a cross-bar a , connected to the rod, as shown in Fig. 2, 40 so that the face-plate may swing on the end of the rod as a pivot during the turning of curves.

Without limiting myself to the precise construction and arrangement of parts shown, I claim as my invention— 45

1. The combination with the platform and frame of a car, of a movable face-plate, a buffer-beam connected with the lower end of the plate, a spring acting upon the buffer-beam, a rod connected with the upper end of the face-plate, a flexible, non-extensible connection extending from the inner end of the rod to the lower end of the face-plate, and guide-pulleys for the said connection, substantially as described. 50

2. The combination with the platform and frame of a car, of a movable face-plate, a buffer-beam connected with the lower end of the plate, a spring acting upon the buffer-beam, a horizontal rod connected with the upper end of the face-plate, a flexible, non-extensible cable extending from the inner end of the rod to the lower end of the face-plate, said cable having its ends lying substantially parallel to the rod and platform respectively, and guide-pulleys for the cable. 60

3. The combination with the platform and frame of a car, of a movable face-plate, a buffer-beam connected with the lower end of the plate, a spring arranged to act upon the buffer-beam, a rod connected with the upper end of the face-plate, a cable extending from the inner end of the rod to the lower end of the face-plate, and guide-pulleys for the cable, one of said pulleys being spring-actuated to maintain the cable taut, substantially 70 as described. 75

In testimony whereof I have signed my name to this specification in the presence of two subscribing witnesses.

CHARLES E. FOSTER.
